(57) **CLAIM**

The ornamental design for an adjustment support member for mounting wall panels to an existing wall, as shown and described.

DESCRIPTION

FIG. 1 is a top perspective view of the adjustment support member for mounting wall panels to an existing wall;
FIG. 2 is a front elevational view thereof, with the rear elevational view being a mirror image thereof;
FIG. 3 is a left side elevational view thereof, with the right side elevational view being a mirror image thereof;
FIG. 4 is a top plan view thereof; and,
FIG. 5 is a bottom plan view thereof.
